JAMES E. DOYLE, OF CLEVELAND, OHIO.

INKING MECHANISM FOR PRINTING PRESSES.

1,403,236.

Specification of Letters Patent. Patented Jan. 10, 1922.

Application filed May 15, 1920. Serial No. 381,720.

To all whom it may concern:

Be it known that I, JAMES E. DOYLE, a citizen of the United States, residing at Cleveland, in the county of Cuyahoga and State of Ohio, have invented certain new and useful Improvements in Inking Mechanism for Printing Presses, of which the following is a specification.

This invention relates to printing presses, and particularly to the inking mechanism therefor. The invention has particular relation to that type of printing press in which the inking rollers travel over an inking platen or rotary inking plate and down across the type form.

The object of the invention is to provide improved inking mechanism for such presses in which the composition inking rollers, of varying sizes on account of shrinkage or expansion, are capable of being adjusted independently of the trucks carrying the rollers and the bearers upon which they travel, thereby giving the proper relation of the varying sizes of composition rollers to the inking plate and type form and the vibrating distributing roller which drives the composition rollers.

A further object of the invention is to provide improved inking mechanism in which the inking rollers are rotated by the vibrator roller which in turn is gear driven from the truck gear, but in which mechanism the inking rollers may be of varying sizes but are nevertheless readily adjustable with relation to the inking plate and type without interfering with said driving arrangement.

Further objects of the invention are in part obvious and in part will appear more in detail hereinafter.

In the drawings, which represent one suitable embodiment of the invention, Fig. 1 is a plan view of the inking rollers and the trucks carrying the same; Fig. 2 is an end elevation from the left in Fig. 1; Fig. 3 is an end view from the right in Fig. 1; Fig. 4 is a sectional plan view on approximately the line 4—4, Fig. 2; Fig. 5 is a front elevation; and Fig. 6 is a sectional elevation on the line 6—6, Fig. 5.

The mechanism shown in the drawings includes the inking plate 1, which may be a platen but usually is a circular plate inclined to the horizontal downwardly from the rear to the front of the press and which is slowly rotated by any suitable mechanism.

On either side of said inking plate are located the extension bearers 2, which are illustrated as angle members with one flange horizontal and serving as a track or support along which the truck rollers of the inking mechanism travel. One bearer is provided with a rack 3 for causing rotation of the vibrator roller, as will later appear. The inking rollers shown are three in number, to wit, two composition rollers 4, both of which are designed to travel in contact with the surfaces of the inking plate and type, and a third or vibrator roller 5, usually of metal, which lies above and contacts with both of the composition rollers 4.

Vibrator roller 5 lies above a cross shaft member consisting of a sleeve 6 (Fig. 4) surrounding the inner ends of two shaft sections 7, which in turn are pinned to inner and outer truck frame members 8, 9, and extend outwardly beyond the same. At their ends these shaft sections receive the upper ends of links or bars 10, which extend downwardly on opposite sides of the press and are connected to suitable operating mechanism, not shown, to traverse the trucks and inking rollers along the bearers across the inking plate and type and back again, as is usual. These links or bars are of well known construction embodying yielding tension means, not shown, to hold the trucks and rollers down upon the bearers with yielding pressure, as is usual.

In each of the truck members are located two non-rotatable sleeves 11, on one of which is journaled a gear 12 meshing with the rack 3 before referred to. On each of said sleeves is also located a plain faced roller 13 provided with roller bearings 14. These four rollers are arranged in pairs, two in alignment with each other on each side of the inking plate, and each of which pairs of rollers travels along one of the extension bearers 2. These rollers and the trucks in which they are journaled therefore serve as the supports for the inking mechanism.

Each of the composition rollers 4 is carried by a sleeve or bushing 15, two of which surround each one of a pair of cross shafts 16, there being one such shaft for each pair of truck rollers. The two shafts 16 extend outwardly through the truck frames and at their ends are provided with blocks 17 held in place at one end of the shaft by a pin 18 and at the other by the head of a screw 19 threaded into the shaft end.

Referring to Figs. 2 and 3, it will be observed that the blocks 17 are of elongated form, being provided in their lower ends with elongated slots 20 to receive clamping screws 21 threaded into depending ears 22 on the truck frames. At their upper ends the blocks are provided with T slots 23 curved lengthwise around the centers of the openings 20, said slots being designed 5 to receive the heads 24 on the lower ends of set screw 25. At each side of each of said blocks is a set screw 26, the inner ones of which are inclined as shown in Fig. 4, to enable them to be more readily manipulated. 10 Shafts 16 where they pass through the openings in the sleeves 11, are smaller in diameter than said sleeves. As a consequence it is possible to adjust each shaft in any direction, either vertically or horizontally, or both, and without disturbing the 20 positions of the sleeves 11. The vertical adjustment enables the composition rollers to be adjusted into proper contacting relation with the inking plate and type, and the horizontal adjustment enables the 25 contacting relation with the vibrator roller always to be preserved. For example, set screws 21 may be loosened and by manipulating the two set screws 26 the blocks 17 30 may be shifted to the right or left. At the same time the screw 25 may be actuated for moving said blocks up or down. After proper adjustment the screws 21 are again clamped. The adjustment is effected without 35 altering the relation between the truck rollers 13 and the bearers on which they travel or the relation between the gear 12 and the rack with which it engages. The construction is particularly advantageous 40 because it enables proper adjustment to be made to compensate for any variations in the sizes of the composition rollers, either as said rollers are replaced by new ones or as they become compacted or shrink in use. 45 The adjustment therefore enables the composition rollers to be made to travel in proper contact with the inking surface and also with the type. This construction is therefore more satisfactory than one where- 50 in the inking plate itself is adjusted relative to the rollers, which adjustment when made does not improve the contacting relation between the inking rollers and type, or other constructions in which the composition 55 rollers are adjusted bodily with the truck rollers and driving gear 12, which disturbs the drive to the rollers.

The gear 12 meshes with a pinion 27 upon the shaft 28 of the vibrator roller 5, which 60 is constructed and is actuated in the manner common in such mechanisms. Without describing such mechanism in detail it is only necessary to state that on one side of the press, as at the left in Fig. 5, the shaft 65 of the vibrator roller telescopes and slides

in the driving sleeve 29 while at the other side said shaft is provided with a threaded portion 30 engaging with a nut 31 so that rotation of said vibrator roller by the gearing before described causes it to travel longitudinally back and forth from side to side of the machine and thoroughly distribute the ink upon the composition rollers. 70

What I claim is:

1. Inking mechanism for printing presses, 75 comprising an inking plate, extension bearers, trucks having rollers movable along the same, inking rollers carried thereby, and means for adjusting said inking rollers relative to said truck rollers.

2. Inking mechanism for printing presses, comprising an inking plate, extension bearers, trucks having rollers movable along the same, a vibrator roller, and inking rollers driven by and adjustable relative to said truck rollers around the axis of said vibrator roller. 85

3. Inking mechanism for printing presses, comprising an inking plate, extension bearers, trucks having rollers movable along the same, a vibrator roller, and inking rollers driven by and adjustable relative to said truck rollers around and toward and from the axis of said vibrator roller. 90

4. Inking mechanism for printing presses, 95 comprising an inking plate, extension bearers, trucks having rollers movable along the same, inking rollers carried thereby, a rack extending along an extension bearer, and a vibrator roller having geared connection to said rack, said inking rollers being driven by and adjustable relative to said vibrator roller and truck rollers. 100

5. Inking mechanism for printing presses, comprising an inking plate, extension bearers, trucks having rollers movable along the same, inking rollers carried thereby, a rack extending along an extension bearer, and a vibrator roller having geared connection to said rack, said inking rollers being 105 driven by and adjustable around the axis of said vibrator roller and relative to said truck rollers. 110

6. Inking mechanism for printing presses, comprising an inking plate, extension bearers, trucks having rollers movable along the same, inking rollers carried thereby, a rack extending along an extension bearer, and a vibrator roller having geared connection to said rack, said inking rollers being 115 driven by and adjustable relative to said truck rollers around and toward and from the axis of said vibrator roller. 120

7. Inking mechanism for printing presses, comprising an inking plate, extension bearers, trucks having rollers movable along the same, sleeves carried by said trucks, and supporting said rollers, a gear on one of said sleeves, a vibrator roller driven thereby, and inking rollers driven by said vibrator 130

roller and adjustable relative to said inking plate and truck rollers.

8. Inking mechanism for printing presses, comprising an inking plate, extension bearing, trucks having rollers movable along the same, sleeves carried by said trucks and supporting said rollers, a gear on one of said sleeves, a vibrator roller driven there-

by, and inking rollers driven by said vibrator roller and adjustable both horizontally and vertically relative to said inking plate and truck rollers.

In testimony whereof I affix my signature.

JAMES E. DOYLE.
